ERNEST FARAGGI, OF PARIS, FRANCE.

DEVICE FOR THE AUTOMATIC STOPPAGE OF SPIRAL SPRINGS.

Application filed December 22, 1921. Serial No. 524,279.

To all whom it may concern:

Be it known that I, ERNEST FARAGGI, a citizen of France, residing at Paris, 6 Avenue du Pont de Flandre, France, have invented certain new and useful Improvements in Devices for the Automatic Stoppage of Spiral Springs, of which the following is a specification.

My invention relates to devices which are employed in combination with apparatus for the automatic mechanical winding of a spring, for the automatic stoppage of the winding of the said spring upon reaching the desired tension. Known apparatus are in use wherein the mechanical winding of a spring is effected by means of a pawl having a reciprocating movement, mounted for instance upon a swinging control arm, and co-operating with a ratchet wheel adapted to draw along in its rotation one end of the spiral spring whereof the other end is stationary. Various devices for the automatic stoppage of the winding have been constructed or proposed for use with the said apparatus, but the known devices of this class present the drawback of an unreliable operation and are subject to failures whereby the winding will be continued beyond the limiting position, thus causing the breakage of the spring.

This invention has for its object a device for the automatic stoppage of the winding movement wherein a reliable and exact operation is obtained. It is principally characterized by the dispositions employed and by the suitable configuration of the ramps of a lever used to arrest the winding movement whereby this stoppage shall take place in two stages; firstly, the disengagement of the winding pawl from the corresponding ratchet wheel, and secondly, the removal of the arm or like support of the pawl to a distance from the member controlling the same and its maintenance in fixed position at a distance from the said member. Another essential characteristic of the invention consists in the fact that the portion or ramp of the lever adapted to arrest the winding operation and effecting the release of the pawl from the ratchet wheel, shall present such configuration with reference to the heel of the said pawl that the pawl shall be maintained out of engagement with said wheel (even though the member carrying the said pawl and effecting a reciprocating movement should not be stopped and

should continue this movement) in all positions of the oscillating movement of the said supporting member.

The accompanying drawing shows by way of example an embodiment of this invention as applied to an apparatus for the mechanical winding of a spring by a shaft actuated by an internal combustion engine, the said spring being disposed in such manner as to effect the starting of the said engine at a subsequent period by the expansion of the same which is controlled by hand.

Fig. 1 is a front view with the cover of the casing removed, showing the position of the mechanical parts at the commencement of the winding of the spring. Fig. 2 is a partial view similar to Fig. 1, showing the position of the parts shortly before the stoppage of the winding and when the stop lever has entered in contact with a cam rotating with the ratchet wheel. Fig. 3 is a similar view, showing the position of the various members when the spring is fully wound. Fig. 4 is a perspective view of a form of construction of the stop lever for the winding operation.

1 indicates the actuating shaft for winding up the spring; 2 is an eccentric mounted upon the said shaft and effecting the alternating movement of an arm 3 which is pivoted to the axle 4 and is caused to bear against the eccentric 2 during the winding operation by a spring 4'. The arm 5 secured to the arm 3 has disposed on the end thereof a pawl 6 which is maintained by a spring 7 in engagement with a ratchet wheel 8. The latter wheel draws with it in its rotation one end 9' of the spiral spring 9 which is to be wound up and whereof the other end 9'' is secured to the casing of the apparatus; 10 is a retaining pawl for maintaining the spring 9 in the wound up position until the unwinding effect of the same is to be used. A heel 11 which serves as an extension of the arm 5 and a heel 12 at the end of the winding pawl 6 are so disposed as to co-operate with a lever 13 provided with a ramp and pivoted to the axle 14, the lever being drawn back towards the centre by the spring 14'. Opposite the stop lever 13 and so disposed as to cooperate with one of the ramps thereof is a cam 15 having two portions of different diameter in such manner as to form an offset 16, the large diameter being greater by an amount at least

equal to the depth of the offset 16 than the diameter assumed by the outer spiral of the spring 9 when the latter has reached the determined limit of tension.

5 According to this invention, the stop lever 13 is provided with four operative portions or ramps.

(a) The first ramp 17 is disposed opposite the spring 9 in such manner as to 10 bear constantly against the outer turn thereof as long as the diameter of the said spiral is greater than the large diameter of the cam 15. The apparatus is so regulated that this condition will prevail as 15 long as the last revolution in the winding of the spring has not been commenced.

(b) The second ramp 18 is disposed opposite the cam 15 in such manner as to bear 20 against the large diameter portion of the said cam after the beginning of the last winding revolution, the diameter of the outer spiral of the spring having now become less than the diameter of the cam. When the ramp 18 drops into the offset 25 16 formed on the small diameter portion of the cam 15, this sudden movement of the lever 13 will arrest the winding motion.

(c) The third ramp 21 is disposed in 30 the plane of the heel 11 of the winding arm; the rear surface 20 of the said ramp is disengaged in order to permit the free movement of the heel 11 during the normal winding operation. The ramp 21 has the shape 35 of a circular arc whose centre is located at 22 (Fig. 1) and is situated at a certain distance from the pivot 14.

(d) The fourth ramp 24 is constituted 40 by a boss 19 situated opposite the heel 12 of the winding pawl. It co-operates with the said pawl in such manner when the ramp 18 drops into the offset 16 of the cam 15, the heel 12 shall be lifted by the ramp 24, thereby releasing the forward end 6 of the pawl from the toothed portion of the wheel 8. The profile of the ramp 24 is so 45 constituted with reference to the shape of the heel 12 that if the said arm 3 should continue its reciprocating movement, the heel 12 would slide upon the ramp 24, thus 50 maintaining the pawl disengaged from the wheel 8 in all the positions of the reciprocating member.

The operation of the said apparatus is as 55 follows. The spring being supposed to be in the unwound position, the stop lever will bear by means of the ramp thereof 17 against the outer spiral of the spring 9 (Fig. 1). When the spring approaches the end of the winding operation and the outer 60 turn has a smaller diameter than the large diameter of the cam 15, the ramp 18 will enter in contact with the latter (Fig. 2); the winding operation still continues, but 65 the stop lever no longer follows the radial movement of the outer spiral of the spring,

inasmuch as it is held in the fixed position by the cam 15. As the rotation of the latter continued during the winding operation, it will arrive at a point at which the small diameter portion thereof will come under 70 the ramp 18 of the lever 13 and the latter will thus be caused to drop suddenly into the offset 16 (Fig. 3); the following will take place; firstly, the ramp 24 will lift the heel 12 of the winding pawl and will 75 separate the latter from the ratchet wheel, thereby arresting the winding operation; secondly, when the arm 3 after being impelled by the eccentric 2 is brought to the left by its return spring 4', the heel thereof 80 11 will enter in contact with the ramp 21. Inasmuch as the latter has an eccentric form, it will impel the heel 11 under the action of the stronger spring 14', thereby causing the arm 3—5 to pivot upon its axle 4, the 85 said arm being thus moved to and maintained in a fixed position out of contact with the eccentric 2 which continues to rotate. It will be seen, therefore, that when the drive shaft 1 is rotated, it will cause 90 the actuation of the eccentric 2 which in turn will impart an alternating, oscillating movement to the lever 3, which is maintained in yieldable engagement with the eccentric 2 by means of the spring 4'. The 95 detent 6, carried by the arm 5, will likewise be given an alternating movement while the ratchet wheel 8 will be advanced by its engagement with the detent 6 and is 100 prevented from moving backward, due to the contact of retaining pawl 10 with the wheel 8. As the ratchet wheel is connected to the end 9' of the spring and since the opposite end 9'' is secured to the casing, a 105 complete winding of the spring will be effected by the rotation of the shaft 1.

A shaft 30 has mounted thereon a retaining pawl 10, and also a bell crank lever 31, the upper arm of which lever is connected to an operating cable 22, while the lower arm thereof has a portion 33 adapted to engage the adjacent face of the pawl 6 when the cable 32 is moved to the right as shown in Figure 1. It will be seen that upon the depression of the lower arm of the lever by 110 movement of the cable 32, the pawl 6 will be disengaged from the ratchet wheel 8, so as to permit the latter to rotate under the tension of the spring 9.

It should be observed that the ramp 24 and the heel 12 of the pawl have a suitable configuration with reference to each other whereby even if the second stage of the operation were not carried out and the winding arm 3 should continue to bear upon the eccentric and to be given the reciprocating movement, the winding pawl will remain 125 separated from the ratchet wheel in all positions of the swing of arm 3, and the heel 12 will slide upon the ramp 24 without per- 130

mitting the point of the pawl to return into engagement with the wheel 8.

The ramps 17 and 18 may be formed in one or may be disposed in alignment without departing from the principle of the invention; however the separation of these two parts into two levels will facilitate the adjustment of the apparatus. In fact, after the apparatus is mounted, the levels 17 and 18 may be regulated with reference to each other for instance by filing the same, in order to adapt their spacing to that which prevails at the beginning of the last winding revolution between the outer spiral of the spring and the periphery of the large diameter part of the cam 15.

Claims—

1. In a device for the automatic stoppage of the winding of a spring, the combination of a notched disc, a pawl releasing lever having a series of separate cam faces, one of which cams normally bears upon the outer turn of the spring and the other being adapted to engage said notched disc, the arrangement of the cams being such that when the spring has been wound, the first cam permits the outer cam to engage the notched disc.

2. In a device for the automatic stoppage of the winding of a spring, the combination of a notched disc, a pawl releasing lever having three separate cam faces, one of which faces normally bears upon the outer turn of the spring, the second cam surface being adapted to cooperate with the notched disc and the third cam surface adapted to cooperate with the pawl, the arrangement of the cam surfaces being such that when the spring has been wound, the first cam surface allows the second cam surface to engage with the notched disc and the third cam surface disengages the pawl from the ratchet wheel.

3. In a device for the automatic stoppage of the winding of a spiral spring, the combination of a ratchet wheel, a notched disc revoluble with said ratchet wheel, a lever having separate cam faces, one of which

faces normally bears upon the outer spiral of the spring and the other being adapted to engage said notched disc, the arrangement of the cam surfaces being such that when the spring has been wound, the first cam surface permits the other to engage the notched disc, a winding lever, and means on the cam lever for stopping oscillation of said winding lever.

4. In a device for the automatic stoppage of the winding of a spiral spring, the combination of a ratchet wheel, a notched disc movable with said ratchet wheel, a lever having separate cam faces, one of which normally bears upon the outer spiral of the spring and another being adapted to engage said notched disc, the arrangement of the cam surfaces being such that when the spring has been wound, the first cam surface permits the other to engage the notched disc, a winding lever, and means on said cam lever for stopping oscillation of said winding lever, said means comprising an additional cam surface formed on the cam lever, the curvature of said additional cam surface being eccentric relative to the turning axis of the cam, and an arm projecting from said lever cooperating with said additional cam surface for holding the latter away from the device when the spring has been wound.

5. In a device for the automatic stoppage of the winding of a spiral spring, the combination of an oscillatory arm having a heel portion, a pawl pivoted to said arm, means yieldably holding said arm in operative position, a ratchet wheel associated with said spring, a cam member rotatable with said spring, a pawl releasing lever having a plurality of cam faces, one of said faces engaging said spring when it is substantially unwound, and another face engaging said rotatable cam member to stop rotation thereof, and a ramp on said lever engageable with said heel to hold said arm against rotation when said spring is fully wound.

In testimony whereof I affix my signature.
ERNEST FARAGGI.
